CLAIM

The ornamental design for a ball tray as shown and described.

DESCRIPTION

FIG. 1 is a perspective view of a ball tray showing our new design;

FIG. 2 is a top plan view thereof;

FIG. 3 is a bottom plan view thereof;

FIG. 4 is a left-side elevational view thereof, a right-side elevational view thereof being a mirror image of the left-side elevational view;

FIG. 5 is a back elevational view thereof; and,

FIG. 6 is a front elevational view thereof.

Broken lines in the figures illustrate environment or portions of the ball tray that form no part of the claimed design.
